UNITED STATES PATENT OFFICE.

WESLEY POWERS, OF PRESTON, NEW YORK.

IMPROVED WINDOW CLOTHES-DRIER.

Specification forming part of Letters Patent No. 37,359, dated January 6, 1863.

To all whom it may concern:

Be it known that I, WESLEY POWERS, of Preston, in the county of Chenango and State of New York, have invented a new and Improved Window Clothes-Drier; and I do hereby declare that the following is a full, clear, and exact description of the same, reference being had to the accompanying drawings, forming a part of this specification, in which—

Figure 1 represents a transverse vertical section of my invention. Fig. 2 is a horizontal section of the same. Fig. 3 is a front elevation of the extension bar or bolt which secures the clothes-drier to a window.

Similar letters of reference in the three views indicate corresponding parts.

The object of this invention is a clothes-drier of that class which can be fastened in a window, and which afford the opportunity for hanging up and drying a large quantity of clothes in the open air without leaving the room or house.

The invention consists in the arrangement of a vertical swivel-bar provided at its ends with gudgeons which fit into sockets, one in the window-sill and the other in a cross-bar secured in the casing of the window, in combination with a series of arms having lines attached to them and fitting into mortises in the swivel-bar in such a manner that said arms, together with the lines attached to them, can be drawn in one after the other by revolving the swivel-bar, and when the clothes are hung on the lines pushed out again, and thus the hanging up of the clothes can be accomplished all, or nearly so, inside the room or house, and without the necessity of extending the arms or any other part of the body out of the window.

The invention consists, further, in the combination, with the swivel-bar and line-carrying arms, of an extension-bar arranged in such a manner that the clothes-drier can be readily adapted to windows of different width.

It consists, finally, in the arrangement of a movable stop in combination with the swivel-bar and window-casing, in such a manner that the swivel-bar, with the line-carrying arms, can be fastened and prevented from swaying about when the clothes are hung to the lines, or released when it is desired to draw in the arms.

To enable others skilled in the art to make and use my invention, I will proceed to describe it with reference to the drawings.

A represents a swivel-bar, made of wood or any other suitable material, and provided with two gudgeons, *a a'*, on each end. The gudgeon *a* is stepped in a socket, *a**, made in the window-sill, and the gudgeon *a'* has its bearing in a cross-bar, B, which is secured at the proper height in the casing of the window at such a distance from the sashes that both, or at least one, sash can be raised and lowered without obstructions. If the wooden sill of the window-casing projects out far enough to receive the socket *a**, a metal plate, *a''*, is secured to the same, as shown in Fig. 1 of the drawings. This metal plate can be dispensed with if the socket has to be made in the stone sill. The cross-bar B, a front elevation of which is shown in Fig. 3 of the drawings, is secured to the window-casing by means of mortises *b*, which retain the end of said bar. If the bar is made to fit a particular window, a sliding bolt may be secured to one or both ends, so that by the action of such bolt or bolts the bar can be fastened or unfastened. I prefer, however, to construct the bar of two parts, which are fastened together by set-screws *b'*, fitting into slots *b**, so that by driving the two parts in or out the length of the bar can be decreased or increased, and thus readily adapted to the width of different windows. The swivel-bar A is perforated with a series of mortises, *c*, to receive the sliding arm C, and said mortises are so arranged in relation to each other that the arms, when in position, stand at angles of about thirty degrees toward each other, as shown in Fig. 2. It is obvious, however, that the number of arms may be increased or diminished at pleasure.

To the outer end of each of the arms C a cross-bar, *d*, is attached, and lines *e* pass through holes *f* near to the inner ends of the arms and through holes at or near the ends of the cross-bar, as clearly shown in the drawings. The outer ends of the arms C pass clear through the cross-bar *d* and project beyond their outer surfaces, so that those portions of the lines which extend along the outer surfaces of the cross-bars are kept off sufficiently far to permit of introducing small articles—such as handkerchiefs or stockings—and, in order to make it still more convenient, small

pieces of wood may be attached to the cross-bars under the lines, for the purpose of keeping them off throughout from the surfaces of said cross-bars. The arms C are made to slide easily in the mortises c, so that they can be pushed out to the position shown in black outlines in Fig. 2, or drawn in one after the other to the position shown in red outlines. If one of the arms is drawn into this latter position, the whole of the line attached to it, or nearly so, is inside the room or house, and the clothes can be hung on the same with the greatest ease and convenience, and after the clothes have been properly secured to the line the arm, together with the clothes, is pushed out, the swivel-bar is turned, the next arm is drawn in and filled with clothes, and so forth, until all the clothes are hung up or all the arms are filled. To prevent the swivel swaying to and fro when the arms are filled with clothes a stop, g, is introduced into the lowest mortise, c*. This stop consists simply of a bar which is sprung over the edges of the window-casing, as clearly shown in Fig. 2, and which can readily be withdrawn whenever it is desired to revolve the swivel-bar and to take in the clothes. The swivel-bar A and arms C are so situated that the window can be closed when the arms are pushed out to their extreme position, so that no inconvenience arises to the persons living in the house or room during the time the clothes-drier is in use. When not

used, the lines are unfastened and the arms C are withdrawn from the sockets in the swivel-bar, and together with the lines stowed away in some convenient place in the house. The swivel-bar may remain where it is, or it can also be taken in, if desired. This clothes-drier is very simple in its construction, it can be made cheap, its operation is easy and readily comprehended by persons of ordinary capacity, and all its parts are so constructed that they do not easily get out of order, and it can readily be adapted to windows of different size and construction.

Having thus fully described my invention, what I claim as new, and desire to secure by Letters Patent, is—

1. The arrangement of a swivel-bar, A, secured by means of gudgeons a a' to the casing of a window, in combination with sliding arms C, provided with lines e, all constructed and operating substantially in the manner and for the purpose herein shown and described.
2. The combination and arrangement of the swivel-bar A, line-carrying arms C, extension-bar B, as and for the purpose specified.
3. The arrangement and combination of the swivel-bars A, line-carrying arms C, and movable stop g, as and for the purpose set forth.

WESLEY POWERS.
